HAND SHARPENER FOR SCISSORS

Joseph Silver and Frank Wallmer,
New York, N. Y.

Application February 20, 1933. Serial No. 657,596

5 Claims. (Cl. 51—205)

This invention relates to an improved and novel hand sharpener for scissors or the like instruments and it is the principal object of our invention to provide a handy and inexpensive tool of simple construction, yet durable and highly efficient in its use.

Another object of our invention is the provision of a hand sharpener, particularly for sharpening the cutting edges of the shanks of a pair of scissors or the like instruments which is equipped with a rotatable disc carrying one of the abrading members and which can be rotated to expose successively new and unused abrading surfaces in order to enable the operator to make full use of the entire abrading surface by a ready adjustment.

Still another object of our invention is the provision of a tool having a handle equipped with corrugated finger holds or grips presenting a firm hold for the instrument during its operation by rapidly moving it along the bevelled cutting edges of the shanks of a pair of scissors to be sharpened while firmly holding the abrading surfaces against the cutting edges.

A further object of our invention is the provision of a hand sharpener for scissors equipped with a means to permit of a convenient adjustment of the abrading surface to suit the particular bevel of the cutting edges of the shanks of a pair of scissors.

A still further object of our invention is the provision of a hand tool for sharpening scissors in which the handle is adjustably held in a suitable frame allowing the adjustment of the angle of the abrading surfaces to suit the angle of the bevel of the cutting edges of the shanks of a pair of scissors, while means are provided to limit the angular displacement of the abrading surfaces to one another.

These and other objects and advantages of our invention will become more fully known as the description thereof proceeds and will then be specifically defined in the appended claims.

In the accompanying drawing forming a material part of this disclosure:

Fig. 1 is a perspective view of a hand sharpener for scissors constructed according to our invention.

Fig. 2 is a side elevation thereof.

Fig. 3 is a rear end view of the sharpener.

Fig. 4 illustrates a modified form of sharpener in rear elevation.

Fig. 5 is a sectional side elevation thereof, the section being taken on line 5—5 of Figure 4.

Fig. 6 is an end elevation of the sharpener, Figures 4 and 5.

Fig. 7 is a perspective detail view of holder, plate and handle.

Fig. 8 is a sectional side elevation of another modified form of our scissors sharpener.

As illustrated in Figures 1—3 the sharpener comprises a holder or handle 10, the side edges of which have integrally formed therewith a pair of substantially circular finger pieces 11, 12 arranged at an angle of substantially 90° to the handle and spaced from one another and corrugated at their outer faces, as at 13 to present a firm gripping face to the fingers of the operator.

The inner end of the handle is widened to form a substantially semi-circular plate 14 angularly bent to the handle at an inclination.

A screw 15 is used to secure a disc 16 to plate 14, and between plate 14 and disc 16 a circular disc 17 of a suitable abrading or sharpening material is removably held to the inner face of disc 16 with two thirds of its area covered by plate 14 while its other third is exposed.

Another disc 18 of likewise abrading or sharpening material is placed against the inner face of plate 14 and covering the same with two thirds of its area while the remaining third of disc 18 is placed and secured in any suitable manner to the underside of handle 10, as at 19.

It will be clear that when the cutting edges of the shanks of a pair of scissors are placed into the angle so formed at the meeting point of the two abrading discs 17, 19, as indicated in broken lines in Figure 1 and the tool is rapidly moved along these edges the same will readily be sharpened to any desired degree. If the exposed part of the disc 17 is worn the screw 15 is loosened and the disc is turned to expose another unused third of its area and if this action is continued also for the exposure of the third part of the abrading face, the usefulness of the abrading surface may be prolonged to its full extent.

In the modified form of our invention illustrated in Figures 4 to 7 the handle 21 has its inner end widened and provided with recesses or sockets 22, 23 in its inner edge for the reception of the tenons 24, 25 of a separate semi-circular plate 26, for the purpose of providing for a relative displacement of both plates to one another.

Plate 26 has a hole 27 allowing the passage of the end of a screw 28 by means of which the outer circular disc 29 is held against plate 26 with the abrading discs 30 and 31 between both.

Also in this form, one third of the abrading disc

30 is exposed, as at 32 while one third of disc 31 is placed against the underside of handle 21, as at 33, while finger rests 34, 35 are provided on the side edges of the handle 21.

- 5 In order to allow an adjustment of the tool to suit the angle of the bevelled cutting edges of the scissors' shanks, the plate 26 has attached to its upper edge the outer end of a curved member 36 having a longitudinally extending slot 37 there-
 10 10 in permitting the passage of a set screw 38 screwed into the outer end of a curved member 39 having its foot part 40 secured to handle 21 by means of rivets 41 or the like.

It will be evident from the above, that besides 15 the turning of the disc 29 to expose another third part 32 of the abrading disc by loosening screw 28 and securing the same again, an adjustment to the angle of the bevel of the cutting edges of the scissors' shank can be obtained by the suitable 20 manipulation of set screw 38.

In the form of our invention illustrated in Figure 8, the handle designated 42 is adjustably held in a frame 43 having at one end formed therewith an arcuate member 44 provided with a longitudinal slot 45 in which a set screw 46 is adjustable the shank of which enters the outer end of handle 42.

Frame 43 has its inner end 47 bent or angularly inclined to frame 43, and carries the abrading member 48 on its outer face, the lower part of which is bent and placed against the lower face of handle 43, as at 49.

The rotatable disc 50, carries a disc 51 of abrading material at its inner face, one third of its area being exposed, as at 52, and a screw 53 secures the disc 51 to handle 42. The member 48 has an opening 54 formed therein through which the handle 42 passes and a shoulder 55 limits the movements of the handle.

40 In use the screw 53 is loosened to allow a rotation of disc 50 to expose another third of its area if one becomes worn, and the screw is then tightened again.

The angular position to suit the particular angle of the bevel of the cutting face of a scissors' shank is changed by means of the suitable and proper adjustment of set screw 46, while shoulder 54 limits the relative movements of frame and handle.

50 It will be understood that we have disclosed the preferred forms of our device only as a few examples of the many possibilities to practically construct our device and that we may make such changes in the general arrangement thereof and in the construction of its minor details as come within the scope of the appended claims without departure from the spirit of our invention and the principle involved.

Having thus described our invention what we claim as new and desire to secure by Letters Patent is:

1. A hand sharpener for scissors comprising a pair of abrading faces set at an angle to one an-

other, one of said faces rotatable, means to successively bring parts of one of said abrading faces into co-operative position with the other of said abrading faces, and means to lock said rotatable face in any of its adjusted positions relative to the other, and means to vary the angles between said faces.

2. A hand sharpener for scissors comprising a handle, a semi-circular plate movably connected to said handle, a rotatable disc, an abrading disc on said semi-circular plate angularly bent to cover part of the underside of said handle, an abrading disc on said rotatable disc, a screw connecting said rotatable disc and the semi-circular plate with the abrading disc between them to permit the exposure of one third of said abrading disc and for locking the parts in their relative adjusted positions; an arcuate slotted member attached at one end to said semi-circular disc and another arcuate member formed with said handle co-operating with said first-named arcuate member to allow an adjustment of the sharpener to suit the bevel of the scissors' cutting edges, and a screw in one arcuate member guided through the slot in the other arcuate member to lock the parts in their relative adjusted positions.

3. A hand sharpener for scissors comprising a handle, a rotatable disc carrying an abrading disc, a means on said handle carrying an abrading disc part of which is set at an angle to the abrading disc on said rotatable disc, a screw connecting said rotatable disc with said handle to allow its rotation and locking in its adjusted position relative to the handle with part of the surface of its abrading disc exposed and at an angle to the abrading disc carried by the handle, and means for adjusting the relative angle of said abrading discs to suit the bevel of the cutting edges of the scissors.

4. A hand sharpener for scissors comprising a frame, a handle adjustably held to said frame at one end, a rotatable disc carrying an abrading disc fitted on the other end of said handle, an abrading disc on said frame having its lower part angularly disposed to the abrading disc on said rotatable disc, and means to limit the angle of relative position of the discs.

5. A hand sharpener for scissors comprising a slotted angular frame, a handle adjustably connected to said frame by a screw passing through the slot in said frame into the handle, and passing through a slot in the opposite branch of said angular frame, an abrading disc partly secured to said branch and to the underside of said frame, a rotatable disc carrying a circular abrading surface angularly disposed to the abrading disc on said frame, a screw securing said disc to said handle at its end passed through said slotted frame branch, and a shoulder formed on said handle for limiting the angles between the abrading discs.
